UNITED STATES PATENT OFFICE.

JOHN D. SCHOONMAKER, OF CAMDEN, NEW JERSEY.

TRIMMER FOR SEWING-MACHINES.

No. 857,491.

Specification of Letters Patent.

Patented June 18, 1907.

Application filed December 26, 1901. Serial No. 87,282.

To all whom it may concern:

Be it known that I, JOHN DAVIS SCHOON-
MAKER, a citizen of the United States, re-
siding at the city of Camden, in the county
5 of Camden and State of New Jersey, have
invented a certain new and useful Trimmer
for Sewing-Machines, of which the following
is a specification.

Objects of the present invention are to pro-
10 vide an efficient, reliable and durable trim-
mer which shall consist of comparatively
few parts of simple construction, to provide
for shifting the trimmer as a whole to widen
and narrow the seam, to hold the knives of
15 the trimmer up to their work adjustably, yet
positively and reliably, to provide for regulat-
ing the angle of the knives in respect to each
other, and to provide for the convenient
application of the trimmer to and its re-
20 moval from the machine.

To these and other ends hereinafter set
forth, the invention comprises the improve-
ments to be presently described and finally
claimed.

25 The nature, characteristic features and
scope of my invention will be more fully un-
derstood from the following description
taken in connection with the accompanying
drawings forming part hereof and in which
30 Figure 1, is a perspective view of a ma-
chine having a trimmer embodying features
of the invention. Fig. 2, is a front view of
the trimmer detached from the machine.
Fig. 3, is an end view of the trimmer showing
35 the knives, and Fig. 4, is a sectional view
taken on the line 4—4, of Fig. 2.

In the drawings 1, indicates an overedge
sewing machine having a driving shaft 2.
The type of machine shown in the drawings
is selected for purposes of illustration and it
is fitted with appliances for making stitches
over or around the edge of the fabric. The
stitching mechanism includes a stitching
needle and a lower hook or hooks (not shown)
5 of well known construction and operation,
for example of the type indicated in U. S.
Patent #602,993, to Frank Malsch.

3, is a bracket which, in use, constitutes
in effect a part of the table of the machine.
This bracket 3, is detachable from the ma-
chine and, as shown, it is provided on its
base with ways 4, that slide on the frame of
the machine. There is an adjusting screw

5, that co-operates with an open bearing 6,
and serves to shift the bracket crosswise of
the line of sewing for a purpose which will
be presently described.

7, is a clamp screw for holding the bracket
3, to place on the machine.

8, is a rocker shaft pivoted to the bracket
3, in such a way that it is afforded slight end-
wise motion in its bearings. This shaft car-
ries a knife holding arm 9, and also an arm
10, which is connected by a link 11, with a
cam on the main shaft 2. This cam serves 65
to rock the shaft 8, and knife holding arm 9.
The pin 12, which connects the arm 10, and
link 11, is detachably screwed into the arm
10, so that it can be taken out to release the
arm 10, when the trimmer is to be taken off. 70
This pin 12, is also permitted to slide end-
wise in the end of the link so as to permit the
trimmer, as a whole, to be shifted trans-
versely of the line of sewing. The arm 9, is
fitted with a split clamping jaw that carries 75
the knife 13. This knife 13, co-operates
with the knife 14, which forms part of or is
secured to the bracket 3. As shown this
knife 14, is mounted in a groove in the end
of the bracket and is clamped or loosened by 80
means of a pin or projection 15, carried at one
end of a pivoted arm 16, of which the other
end is provided with a clamping screw 17, so
that when the latter is shifted, the pin is
made to bind or free the knife 14. 85

18, is a set screw whose point bears upon
the end of the shaft 8. Thus by turning the
set screw 18, it is possible to shift the shaft 8,
endwise and thus cause the knives 13 and 14,
to bear upon each other, so that it is the set 90
screw 18, which holds the knives up together
laterally into position for doing their work.

19, is a finger or guide connected with the
trimmer and over which the thread of the
stitches is laid, so that when the bracket 3, is 95
moved transversely of the line of feed, this
guide 19, as well as the knives, is also moved
and this seam is widened or narrowed.

By loosening the screw 20, it is possible to
adjust the inclination of the arm 9, in respect 100
to the arm 10, so as to change the inclination
of the knife 13. The face 21, of the bracket
3, serves to deflect the trimmed material.

It will be obvious to those skilled in the
art to which my invention appertains that 105
modifications may be made in detail without

departing from the spirit thereof, hence I do not limit myself to the precise construction and arrangement of parts hereinabove set forth and illustrated in the accompanying drawings, but

Having thus described the nature and objects of my invention, what I claim as new and desire to secure by Letters Patent is:

The combination of an overedge sewing machine, a detachable bracket having ways that slide on the frame of the machine, and provided at one end with an angular slot, an open bearing secured to the frame, an adjusting screw accommodated in said bearing for shifting the bracket longitudinally in respect to the frame, a rocker shaft journaled in the bracket with provision for endwise adjustment, a knife slidably mounted in said slot,

a pivotal arm 16 for binding and releasing said knife, a clamping screw whereby said arm may be adjusted, a co-operating adjustable vibrating knife carried by the rocker shaft, a main driving shaft, and operative connections intermediate the latter and the rocker shaft such that the trimmer may be removed, said bracket having a guide 19, over which the thread is laid and having a part 21, to deflect the trimmed material, substantially as specified.

In testimony whereof I have hereunto signed my name.

JOHN D. SCHOONMAKER.
